UNITED STATES PATENT OFFICE.

ATHA W. LEE, OF BINGHAM CANYON, UTAH.

CIGARETTE PACKAGE.

Application filed February 5, 1925. Serial No. 7,118.

My invention relates to improvements in packages for cigarettes and other articles, of the type in which a ripping cord is provided to open the package. In packages of this type heretofore provided, the ripping cord usually tears a very jagged cut, and very often the package will also tear laterally from the line on which the ripping cord is located. It is the primary object of my invention, to provide a simple and unique construction for overcoming this difficulty.

A further object of the invention is to provide a package-opening, ripping cord having one of its end portions anchored beneath a lacerable seal for the package, for instance, the ordinary revenue stamp of a cigarette package.

With the foregoing in view, the invention resides in the novel subject matter hereinafter described and claimed, the description being supplemented by the accompanying drawing.

Figure 1 is a perspective view of a sealed package constructed in accordance with my invention.

Figure 2 is a vertical sectional view through the upper end portion of the package, part of the contents being broken away to more clearly disclose the ripping cord and the reinforcing strips between which it is located.

Figure 3 is a view similar to Fig. 1 but illustrating the package partly opened.

Figure 4 is a perspective view showing the package fully open.

Figure 5 is a perspective view illustrating the reinforcing strips between which the ripping cord is confined.

In the drawing above briefly described, a conventional form of cigarette package has been shown, including opposed vertical side walls 1, and a vertical edge wall 2, as well as a top 3 which is sealed by the usual stamp or other seal 4. Vertically spaced, closely related, reinforcing strips 5 and 6, preferably formed of cardboard, are located within the package, the intermediate portions of said strips extending horizontally across the edge wall 2, near the upper end of the latter, while the end portions 5^a and 6^a of said strips extend across portions of the side walls 1, said strips being glued or otherwise secured to the walls 1 and 2. In the construction shown, the extremities of the end portions 5^a are curved as at 5^b, and the

extremities of the end portions 6^a turn upwardly as at 6^b, around and in close relation with said curved extremities 5^b.

Glued to the inner sides of the walls 1 and 2, between the strips 5 and 6, or otherwise suitably secured to said walls, is a ripping cord 7, the end portions of said cord being shown extended upwardly as at 8, passed through openings 9 in the walls 1, to the exterior of the package, and then anchored beneath the seal 4. By this arrangement, pulling of either end of the cord 7, will first tear the seal 4. Then, the remainder of the cord will tear the package vertically and also tear it horizontally between the strips 5 and 6, so that an upper corner of the package is cut loose from the major portion of the latter, providing a hinged cover C (Fig. 4) whose lower edge is reinforced by the strip 5, while the upper edge of the portion of the package which co-acts with said cover, will be similarly reinforced by the strip 6. Thus, repeated opening of the cover will not materially injure it or the co-acting portion of the package, and it is obvious that when this cover is swung open, the cigarettes or other contents of the package may be readily removed. If desired, the cover may of course be entirely torn from the package, but this is not necessary.

Attention is directed to the fact that in addition to forming reinforcements for the cover C and the co-acting portion of said package, the strips 5 and 6 effectively confine tearing of the package walls, to the line followed by the ripping cord 7, between said strips. It is not usually necessary that the vertical portions of the cord be confined also between portions of the reinforcing strips, as in most instances, the grain of the paper permits it to tear easily and straight. However, if desired, it will be understood that the scope of the invention is such as to permit use of reinforcing strips on any wall or walls of the package, at opposite sides of the ripping cord. Whenever this is done, a substantially clean cut is insured, instead of allowing jagged tearing as very often happens without the use of the reinforcing strips.

It will be seen from the foregoing that a very simple, inexpensive and desirable package has been provided, and while excellent results are obtainable from the preferred form of construction herein disclosed,

it is to be understood that within the scope of the invention as claimed, modifications may be made.

I claim:

- 5 1. A package formed of lacerable material and including opposed vertical side walls, and a vertical edge wall at substantially right angles to said side walls, upper and lower closely related reinforcing strips within the package having their intermediate portions secured horizontally across said edge wall near the upper end of the latter, said strips having end portions extending horizontally across and secured to portions 10 of said side walls, the extremities of the lower strip being turned upwardly around and in spaced relation with the extremities of the upper strip, and a ripping cord secured in the space between said strips and 15 having upwardly directed end portions at the extremities of said strips, at least one

of said end portions of the cord being extended to the exterior of the package.

2. A package formed of lacerable material and including opposed vertical side walls, 25 and a vertical edge wall at substantially right angles to said side walls, upper and lower closely related reinforcing strips within the package having their intermediate portions secured horizontally across said 30 edge wall near the upper end of the latter, said strips having end portions extending horizontally across and secured to portions of said side walls, and a ripping cord secured in the space between said strips and having 35 upwardly directed end portions at the extremities of said strips, at least one of said end portions of the cord being extended to the exterior of the package.

In testimony whereof I have hereunto 40 affixed my signature.

ATHA W. LEE.
